UNITED STATES PATENT OFFICE.

CHARLES J. CARLISLE, OF COLDWATER, MICHIGAN.

TOY MAGAZINE-RIFLE.

1,148,753.

Specification of Letters Patent. Patented Aug. 3, 1915.

Application filed April 12, 1915. Serial No. 20,918.

To all whom it may concern:

Be it known that I, CHARLES J. CARLISLE, a citizen of the United States, residing at Coldwater, in the county of Branch and State of Michigan, have invented a new and useful Toy Magazine-Rifle, of which the following is a specification.

This invention relates to a toy magazine rifle, one of its objects being to provide a rifle having a magazine located along the barrel and which is provided with a reciprocating element designed, when shifted in one direction, to set the trigger of the rifle and, when shifted in the opposite direction, to direct a projectile from the magazine and into the barrel of the rifle.

A further object is to provide means whereby a projectile, when once discharged into the barrel, will be yieldingly retained so that, should the rifle be held with its muzzle pointed downwardly, there would be no danger of the projectile gravitating therefrom.

A further object is to provide a toy magazine rifle which is simple and inexpensive in construction and which bears a close resemblance to the usual form of magazine rifle.

Another object is to provide a rifle having a magazine in which the projectiles can be readily placed, there being means combined with the magazine for preventing the projectiles from becoming accidentally released from the magazine when the rifle is held with its muzzle down.

With the foregoing and other objects in view which will appear as the description proceeds, the invention resides in the combination and arrangement of parts and in the details of construction hereinafter described and claimed, it being understood that changes in the precise embodiment of the invention herein disclosed, can be made within the scope of what is claimed, without departing from the spirit of the invention.

In the accompanying drawings the preferred form of the invention has been shown.

In said drawings:—Figure 1 is a central longitudinal section through the rifle, the stock being broken away and the parts being shown in the positions assumed thereby immediately after the setting of the trigger and prior to the direction of a projectile into the barrel, the positions of the projectile immediately upon being directed into the

barrel and when subsequently brought to loaded position, being indicated by dotted lines. Fig. 2 is a view similar to Fig. 1 and showing the positions assumed by the parts after a projectile has been fired. Fig. 3 is a section on line A—B Fig. 1. Fig. 4 is a section on line C—D Fig. 1. Fig. 5 is a section on line E—F Fig. 1. Fig. 6 is a section on line G—H Fig. 1. Fig. 7 is a section on line I—J Fig. 1.

Referring to the figures by characters of reference, 1 designates the barrel of the rifle, the same being formed, in the present instance, of sheet metal having integral longitudinal wings bowed transversely to form a tubular magazine 2.

As shown in Figs. 1 and 3 this tubular magazine is extended for a portion of the length of the barrel 1, and one of the wings constituting the magazine walls is provided, at its rear end, with an integral tongue 3 intersecting the rear portion of the magazine and provided with flat faces, the front end of said tongue being inclined, as at 4 so as to constitute means for deflecting a projectile toward the barrel 1 from the magazine 2. The sides of the barrel 1 and magazine 2 are cut away close to the inclined end 4 of the tongue 3 to form an opening 5 through which communication is established between the magazine 2 and the barrel 1, the metal removed in the formation of this opening being extended in parallel planes to form flat sides 6 extending from the barrel 1 to opposed portions of the magazine 2, as shown in Fig. 4.

The rear portion of the barrel 1 is provided along the bottom thereof with oppositely bowed wings 7 forming a tubular casing 8 which extends rearwardly beyond the barrel and, with said rear portion of the barrel, is seated within the stock 9 of the toy rifle. The casing 8 constitutes a housing for a coiled spring 10 and one end of the spring is formed with a stem 11 having a loop 12 and extending through a slot 13 formed between barrel 1 and the tubular casing 8, said pin being preferably bent in the form of a loop, as shown particularly in Figs. 6 and 7, thus to constitute a head for engaging the projectile.

A trigger 14 in the form of a bell crank lever is pivotally mounted in an opening 15 in the stock and the inner arm of this trigger extends through an opening 16 in an ear 17 which extends downwardly from one

end of a spring catch 18 which is secured to the stock 9 and projects normally through an opening 19 in the bottom of casing 8, thus to engage stem 11 and hold it against the action of the spring 10.

A rod 20 is slidably mounted within the casing 8 and the magazine 2, the forward end of this rod being beveled as shown at 21 and being also forked or slotted, as at 22 10 so as to thus straddle the tongue 3. The rear end of rod 20 is adapted to bear against stem 11 when said rod is drawn rearwardly and the sliding movement of the rod relative to the magazine 2 and the casing 8 is limited 15 by a grip 23 formed on or secured to the rod and working between the magazine 2 and the casing 8.

A light leaf spring 24 is secured within the rear portion of the barrel 1, its free end being extended rearwardly so that when a projectile gravitates downwardly into the barrel 1, it will come against this spring 24 and be lightly gripped thereby and thus be held 20 against displacement from the barrel when 25 said barrel is held with its muzzle down.

A spring strip 24' extends into the front or open end of the magazine 2 and serves to retain the projectiles loaded into the magazine. This spring strip can be made integral with the barrel 1 or can be formed in a separate piece, as preferred. A trigger guard 25 may be secured to the stock and extended under the trigger 14 so as to prevent it from being accidentally actuated.

35 When it is desired to use the toy rifle constituting the present invention, a series of balls to be projected is inserted into the magazine 2, they being retained in the magazine between the spring 24' and the beveled 40 end 21 of the rod 20, said rod being normally positioned to close the opening 5, as shown particularly in Fig. 2. By now pulling rearwardly on the grip 23, rod 20 is caused to withdraw from across the opening 45 5 so that the projectile engaged by the end of rod 20 will be permitted to move against the inclined edge 4 of tongue 3 and into position directly under the opening 5. During the rearward movement of rod 20 it 50 comes against the stem 11 and thrusts the stem rearwardly against the action of spring 10. During this rearward movement of stem 11 the convolutions of the spring pass over the latch 18 and said latch springs in 55 front of one of the convolutions and holds the stem in the position to which it has been moved. By now pushing the rod 20 forward by means of grip 23, the beveled end 21 of the rod will work under the projectile 60 below the opening 5 and will thrust said projectile upwardly through said opening, the rod moving to position to close the opening and prevent any more projectiles from entering the barrel 1. During this action of 65 the rod 20 the rifle is held naturally in an

inclined position with the stock lowermost and as soon as the projectile enters the barrel 1 it will gravitate within said barrel and come against the loop 12 and be retained lightly by the spring 24. Thus the projectile will be held until the trigger 14 is actuated, whereupon the latch 18 will be withdrawn from in front of the spring 10 and the stem 11 will be propelled forwardly under the action of spring 10, thus ejecting the projectile in the path of the loop 12. By now pulling backwardly on rod 20 the foregoing operation will be repeated, the stem 11 being reset and a projectile allowed to gravitate against the edge 4 of the tongue 3. When rod 20 is pushed forward said projectile will be thrust into barrel 1.

It will be noted that the barrel, magazine and the casing 8 can all be formed in one piece of sheet metal, thus materially lessening the cost of the rifle. Obviously, however, the barrel, magazine and casing 8 can be made of separate tubular members if so desired, the same being soldered or otherwise connected.

What is claimed is:—

1. A toy magazine rifle including a barrel, a tubular magazine extending therewith and communicating therewith through an opening adjacent one end of the magazine, a deflector within the magazine and adjacent the opening, a spring mounted adjacent the barrel, means extending from the spring and into the barrel for engaging and propelling a projectile, a means for engaging the spring to hold it under compression, and a rod slidably mounted relative to the barrel and constituting means, when moved in one direction, for setting the spring and, when moved in the opposite direction, for expelling a projectile from the magazine and into the barrel and for closing the opening between the magazine and barrel.

2. A toy rifle including a barrel, a magazine, and a tubular casing adjacent the respective end portions of the barrel and disposed in alignment, there being an opening for maintaining communication between the magazine and barrel, a projectile engaging element movably mounted within the barrel and casing, a spring for holding said element normally in a predetermined position, means for locking the element against the action of its spring, and a rod slidably mounted within the magazine and casing and constituting means when shifted in one direction for setting the projectile engaging means and, when moved in the opposite direction, for directing a projectile from the magazine and into the barrel.

3. A toy rifle including a barrel, a magazine, and a casing, said magazine and casing alining and said magazine communicating with the barrel through an opening, a com-

5 bined stop and deflector within the magazine and adjacent the opening, spring controlled projectile actuating means within the casing and barrel, means for automatically holding the same against the action of its spring, and means mounted for reciprocation within the magazine and casing for successively setting said projectile actuating means and for expelling a projectile from 10 the magazine and through the opening into the barrel.

4. A toy rifle including a barrel, a magazine communicating therewith through an opening, a casing, said magazine and casing 15 alining, a combined stop and deflector within the magazine and adjacent the opening, a spring within the casing, means carried thereby for engaging a projectile within the barrel, a spring latch for engaging the 20 spring to hold it under compression, means for actuating the latch to release the spring, and means slidably mounted within the magazine and casing for setting the spring and for ejecting a projectile from the 25 magazine and through the opening into the barrel.

5. In a toy rifle, a barrel formed of sheet metal and having opposed longitudinally extending bowed wings coöperating to form 30 a cylindrical magazine in communication with the barrel, additional opposed longitudinally extending bowed wings coöperating to form a tubular casing back of the magazine, there being a longitudinal slot 35 for maintaining communication between the casing and barrel, and deflecting means integral with the first mentioned wings and within the magazine.

6. A toy rifle including a barrel, a magazine 40 communicating therewith through an opening, a tongue within one end portion of the magazine and having an inclined edge constituting a deflector, a spring within the magazine for retaining projectiles therein, 45 spring controlled means for expelling a projectile from the barrel, a latch for engaging said means to hold it against movement,

a trigger for actuating the latch to release said means, and means for successively setting said spring controlled means and ejecting a projectile from the magazine and into the barrel. 50

7. A toy rifle including a barrel formed of sheet metal and having opposed longitudinally extending bowed wings constituting 55 a tubular magazine and a tubular casing adjacent the end portions respectively of the barrel, a tongue integral with one of the wings forming the magazine and bisecting one end portion of the magazine, said tongue having an inclined forward end constituting a deflector, there being an opening between the magazine and the barrel adjacent the inclined end of the deflecting tongue, a spring within the casing, means 60 thereon for engaging a projectile within the barrel, a spring latch engaging the spring to hold it under compression, a trigger engaging the latch to move it from engaging position, and a rod slidably mounted within 65 the magazine and casing, said rod having a forked end straddling the tongue within the magazine and said end being beveled to constitute means for ejecting a projectile from the magazine through the opening into 70 the barrel. 75

8. In a toy rifle, a barrel formed of sheet metal and having opposed longitudinally extending bowed wings forming a cylindrical magazine and a tubular casing back 80 of the magazine, and a tongue integral with one of the wings and bisecting one end portion of the magazine, said tongue having an inclined deflecting end, there being an opening between said magazine and barrel and 85 close to said end.

In testimony that I claim the foregoing as my own, I have hereto affixed my signature in the presence of two witnesses.

CHARLES J. CARLISLE.
